UNITED STATES PATENT OFFICE.

FRANK H. NALL, OF EVANSVILLE, INDIANA.

DESIGN FOR A LAMP-PEDESTAL BASE.

Application filed February 26, 1924. Serial No. 8,747. Term of patent 3½ years.

To all whom it may concern:

Be it known that I, FRANK H. NALL, a citizen of the United States, residing at Evansville, in the county of Vanderburg and State of Indiana, have invented a new, original, and ornamental Design for Lamp-Pedestal Bases, of which the following is a specification, reference being had to the accompanying drawing, forming part thereof.

I claim:

The ornamental design for a lamp pedestal base, as shown.

FRANK H. NALL.
